(57) **CLAIM**

The ornamental design for a front member for a support mechanism for a wheelchair, as shown and described.

DESCRIPTION

FIG. 1 is a front perspective view of a front member for support mechanism of a wheelchair according to our new design,

FIG. 2 is a rear perspective view thereof,

FIG. 3 is a left side elevational view thereof when in an open positioning of elements, the right side elevational view being a mirror image,

FIG. 4 is a left side elevational view thereof when in a closed positioning of elements, the right side elevational view being a mirror image,

FIG. 5 is a left side elevational view thereof when in an intermediate positioning of elements, the right side elevational view being a mirror image,

FIG. 6 is a front elevational view thereof; and,

FIG. 7 is a rear elevational view thereof.
